(57) **CLAIM**

The ornamental design for a lawn mower, as shown and described.

DESCRIPTION

FIG. 1 is a perspective view of a lawn mower, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1;

FIG. 10 is another enlarged view of portion of FIG. 1;

FIG. 11 is an enlarged view of portion of FIG. 2; and,

FIG. 12 is another enlarged view of portion of FIG. 2.

The long dash short dash broken lines illustrated in FIGS. 1, 2, and 9-12 are included for the purpose of indicating the boundary in which the enlarged views are shown, the broken lines form no part of the claimed design.
